O. I. RONNINGEN

BREECH PROTECTOR FOR FIREARMS

Filed Sept. 25, 1923

INVENTOR.

O. I. Ronningen

BY

Geo. P. Kimmel, ATTORNEY.

UNITED STATES PATENT OFFICE.

OTTO I. RONNINGEN, OF MADISON, MINNESOTA.

BREECH PROTECTOR FOR FIREARMS.

Application filed September 25, 1923. Serial No. 664,729.

To all whom it may concern:

Be it known that I, OTTO I. RONNINGEN, a citizen of the United States, residing at Madison, in the county of Lac Qui Parle and State of Minnesota, have invented certain new and useful Improvements in Breech Protectors for Firearms, of which the following is a specification.

This invention relates to shield devices 10 adapted to be attached to the breech portions of fire arms, such as rifles, shot guns and the like, to protect the breech mechanism without interfering with the operation of the loading, firing or shell discharging devices, or otherwise interfering with its 15 ordinary uses.

Another object of the invention is to provide a device of this character, which may be adapted without material structural change 20 to fire arms of various makes or construction.

With these and other objects in view the invention consists in certain novel features of construction as hereinafter shown and described and then specifically pointed out in the claim, and in the drawings illustrative of the preferred embodiment of the invention—

Figure 1 is a side elevation of the improved device applied to a conventional fire 30 arm.

Figure 2 is an enlarged detached perspective view of the improved device turned on its side.

Figure 3 is an enlarged transverse section 35 on the line 3—3 of Fig. 1 looking in the direction of the arrow.

The improved device includes a guard or shield represented as a whole at 10, of sheet metal as light as possible consistent with the 40 strains to which it will be subjected, and generally in inverted U shape transversely. The member 10 will be fitted to engage over the breech mechanism of a fire arm, such as a rifle, shot gun or the like, and will be varied 45 to conform to the outlines of the weapon to which it is applied.

For the purpose of illustration the device is shown in Fig. 1 applied to a conventional army rifle in which 10 represents the butt, 11 50 the stock, 12 the barrel, and 13 the trigger guard of the usual construction.

The improved shield when applied to a rifle having a lateral pin 14 is provided with a slot 15 through which the pin extends and 55 through which it is operative, and the slot

is provided with a swinging closure 16, held in place by a sliding pin 17.

The details of the construction of the shield may be varied to adapt it to the construction of the fire arm to which it is applied.

Attached to the shield represented as a whole at 24 at one side is a rod 18 extending beyond the forward end of the shield at one end. The rod 18 is shown engaged in a tubular portion 19 rolled from one edge of the member represented as a whole at 24 and extending for a portion only of the length of the shield, as shown in Fig. 2.

Slidable over the rod 18 is a tubular support 20, and attached at 21 to the support are divided clamping bands 22. The ends of the bands being coupled by suitable fastening devices represented conventionally at 23 and operating to apply strain to the bands.

The bands are designed to be clamped around the barrel 12 and stock 11 of the fire arm, as indicated in Fig. 1, and readily adapt themselves to the differences in the 80 contour of the weapon, and serve to couple the shield in position.

The breech cover opens and closes with the opening and closing of the bolt on a bolt action fire arm, making it unnecessary to remove the cover to fire or reload, and this operation is accomplished without slowing up the action of the weapon mechanism, or adding appreciably to or increasing the muscular force of the operator. It requires only about 90 one second of time to detach the cover member.

The improved device is simple in construction, can be inexpensively manufactured, and applied to various forms of fire arms 95 and effectually protects the breech mechanism from moisture, dust, or the like, without interfering with the sighting or firing of the weapon.

The parts are so constructed that no portions project to catch on the clothing or surrounding objects.

The preferred embodiment of the invention is disclosed in the drawings and set forth in the specification, but it will be 105 understood that modifications within the scope of the claimed invention may be made in the construction without departing from the principle of the invention or sacrificing any of its advantages.

Having thus described the invention, what is claimed as new is:

A device of the class described comprising a shield element adapted to engage over the breech portion of a fire arm, a longitudinally directed guide rod extending in advance of the shield element, a tubular member slidably engaging said rod, divided at

taching bands in spaced relation connected to said tubular member and means adapted to compress said bands on the arms structure. 10

In testimony whereof, I affix my signature hereto.

OTTO I. RONNINGEN.
